UNITED STATES PATENT OFFICE.

NELSON WILLIAM ALDOUS, OF TORONTO, CANADA.

CARPET-CUTTER AND THE LIKE.

No. 820,692.

Specification of Letters Patent.

Patented May 15, 1906.

Application filed July 20, 1905. Serial No. 270,573.

To all whom it may concern:

Be it known that I, NELSON WILLIAM ALDOUS, of the city of Toronto, in the county of York, in the Province of Ontario, Canada, have invented certain new and useful Improvements in Carpet-Cutters and the Like, of which the following is a specification.

My invention relates to improvements in carpet-cutters and the like; and the object of the invention is to devise a simple, neat, efficient, and durable carpet-cutter whereby the carpet or the like may be easily, quickly, and cleanly cut; and it consists, essentially, of a frame, a discus-shaped wheel, a roller acting in conjunction with said wheel, and rollers supporting said frame, all arranged as hereinafter more particularly explained.

Figure 1 is a perspective view of my carpet-cutter. Fig. 2 is a cross-sectional view of the carpet-cutter through the center of the discus-shaped wheel and in a plane at right angles to the plane of the wheel.

In the drawings like figures of reference indicate corresponding parts in each figure.

A is the disk or discus-shaped wheel, supported in suitable bearings A'.

B is the frame, having a convenient and substantial handle as a portion thereof or attached thereto, and C is a spiked, roughened, or corrugated surfaced wheel supported in suitable bearings in the frame and having a groove with a perpendicular and a slant side, the perpendicular forming a knife-edge, which, together with the sharp periphery of the discus-shaped wheel, forms the cutting-surfaces of the machine.

D are rollers having a rubber covering E, whose surfaces by engagement with the surface of C give to it a rotary motion, and thus help to feed the carpet or the like to the cutting-surfaces, and at the same time perform the function of rollers on which the frame rests.

E is a suitable brace or support which prevents any tendency of breakage in the frame due to the stress of bending movement.

The operation is as follows: The material to be cut is placed between the cutters A and C, the rollers D resting upon the table. The device is then moved forward, and as the rollers D move they impart movement to the cutter C.

It will be seen that with a cutter such as I describe a simple and effective means of producing the desired result has been found and should prove itself to be a necessary acquisition to those engaged in a business requiring such device.

What I claim as my invention is—

A carpet-cutter consisting of a frame, a sharp disk mounted therein, a roller having a circumferential groove also mounted in the frame below said disk, one side of the groove being inclined and the other perpendicular to form a cutting edge, said disk engaging with said cutting edge and friction-rollers engaging with the grooved roller to impart motion to the same.

NELSON WILLIAM ALDOUS.
